UNITED STATES PATENT OFFICE.

HENRY F. REUTER, OF NASHVILLE, ILLINOIS.

DESIGN FOR A TACK.

SPECIFICATION forming part of Design No. 28,350, dated March 8, 1898.

Application filed January 7, 1897. Serial No. 665,977. Term of patent 14 years.

To all whom it may concern:

Be it known that I, HENRY F. REUTER, of Nashville, in the county of Washington and State of Illinois, have invented and produced 5 a new and original Design for a Tack, of which the following is a full, clear, and exact specification.

Reference is to be had to the accompanying drawings, forming a part of this specification, 10 in which similar characters of reference indicate corresponding parts in all the figures.

Figure 1 is a side elevation of a tack, showing my design. Fig. 2 is a cross-section of the same on the line 2 2 of Fig. 1. Fig. 3 is 15 a plan view of the same, and Fig. 4 is a sectional plan view of the same on the line 4 4 of Fig. 1.

The invention relates to double-pointed tacks.

20 The leading feature of the design consists of the prongs A A', having their inner oppo-

site faces A² A³ flat and parallel one to the other, the side edges A⁴ of each prong terminating in a point, as is plainly shown in Fig. 2. The inner or under half-round surface B' 25 of the arch-shaped head, B terminates in the flat inner faces of the prongs A A' and the sides B² of the head taper outwardly and upwardly from the tapering sides A⁴ of the prongs A A'. The outer surface of the head 30 B has a flat face B³ at the top of the head, which tapers from the face B³ to the side edges B², and is rounded off at the sides to merge into the outer surfaces of the prongs A A'. 35

I claim—

The design for a tack, as herein shown and described.

HENRY F. REUTER.
